UNITED STATES PATENT OFFICE.

JOHN T. CARTER, OF JEFFERSON CITY, MISSOURI.

DISH-WASHING DEVICE.

1,328,942.

Specification of Letters Patent. Patented Jan. 27, 1920.

Application filed August 13, 1918. Serial No. 249,734.

To all whom it may concern:

Be it known that I, JOHN T. CARTER, a citizen of the United States, and a resident of Jefferson City, in the county of Cole and State of Missouri, have invented certain new and useful Improvements in Dish-Washing Devices, of which the following is a specification.

This invention relates to washing apparatus, and more particularly to dish washing devices, and has for an object to provide a simple cheap and efficient portable device whereby dishes may be washed in a drain without the necessity of exposing the hands to the washing fluid. Another object of the invention is to produce a device wherein the soap or detergent used will be effectually mixed with water and the resulting mixture delivered onto the dishes without the hands of the user coming in contact with either the dishes or the soapy mixture. A further object is to provide a device that can be quickly attached to and removed from the ordinary house spigot in the operation of washing dishes.

With the above and other objects in view, the invention consists in a casing having inlet means for attachment to a spigot, an outlet, and a foraminous soap container within the casing intermediate the inlet and outlet.

The invention consists further in a casing having an inlet adapted for attachment to a spigot, an outlet, and horizontally rotatable foraminous soap container or cage positioned intermediate the inlet and outlet.

The invention consists further in a casing having an inlet tube, an outlet tube, a soap container or cage rotatably mounted within the casing, and means in the outlet tube, for causing a whirling motion to the liquid passing through said tube.

The invention consists further in a casing, means carried by the casing for attachment to a spigot, an outlet pipe, a soap container or cage mounted to rotate horizontally within the casing, and means carried by the cage for causing rotary movement of the same by passage of water through the casing and outlet tube.

The invention consists further in certain novel features of construction, arrangement, and combination of parts as will be hereinafter described and pointed out in the claims, reference being had to the ac-

companying drawings forming a part thereof, in which—

Figure 1 is a vertical longitudinal section of my device as applied,

Fig. 2 is an elevational perspective view 60 of means carried by the discharge or outlet tube to cause whirling motion of the washing mixture, and

Fig. 3 is a top plan view of the soap container or cage. 65

In carrying out my invention, I employ a circular casing comprising the lower member 5 and the upper member 6, the upper member being expanded at its lower end and fitting snugly over the upper edge of 70 the lower member, the two members being locked together preferably by a bayonet joint 7 including an L-shaped groove and a projection fitting therein, so that the members may be readily connected and separated. 75

Extending upwardly from the upper member is the inlet or supply tube 8, which is adapted to be fitted to a section of hose 9, which may be attached to the ordinary 80 house spigot used in kitchen sinks.

Extending downwardly from the lower member 5 is the outlet or discharge tube 10 which tapers downwardly and has soldered or rigidly mounted therein a thin web or 85 fin 11 which is given a spiral twist or turn similar to a spiral conveyer. At the upper end of the fin a bearing pin 12 is applied, the lower end of the pin being split or bifurcated and straddling the said fin, it being 90 soldered in place.

The soap container which consists of a lower foraminous basket like structure 13 and an upper imperforate cap 14 is rotatably supported on said pin 12 by a tubular post 95 or socket 15 extending downwardly from the basket to which it is soldered by a flange 16, and fitting onto said pin.

The cap or cover 14 for the basket consists of a cone-shaped top 17 and a flange 100 18 extending from the underside thereof and fitting within the foraminous basket member, the periphery of the cap projecting slightly beyond the side walls of the basket.

The upper face of the cone-shaped cap is 105 provided with curved vanes 19 placed on edge and radially disposed from the apex to the circumference of the cap.

It will be noticed that the apex of the cone-shaped cap is immediately below the 110

inlet to the casing, the purpose of the arrangement being to insure the water under pressure entering the casing, striking the vanes and the impact causing rotation of 5 the soap container or cage in a horizontal plane.

To use the device, the hose section is applied to the outlet of the house spigot, the lower member of the casing detached from 10 the upper member by a simple turning and pulling movement; the cap of the cage is removed and the basket filled to the desired degree with particles of soap or other detergent, the cap replaced, and the lower 15 member of the casing which carries the soap cage, is again coupled to the upper member 6 by the bayonet joint connection, and the valve of the spigot opened. The device can then be used to wash the dishes 20 which can be done in a very few minutes, as the rotary movement of the soap container insures a quick mixing of water and soap and this mixture is delivered from the outlet tube with a whirling motion which 25 renders it very much more effective than if delivered in a direct current.

By attaching the device to a spigot, it can be moved to different parts of the sink or dish holding device, very quickly, so that 30 the washing and cleansing is almost instantaneous, and during the entire operation, the hands need not come in contact with the water or soapy mixture; this latter feature is a very desirable and important feature of the use of my device. 35

From the above it will be understood that I provide an extremely simple, cheap, and efficient dish-washing means, that relieves the operation of its drudgery and ill effects upon the hands of the user. 40

I claim:—

1. A device as characterized and comprising a two piece separable casing, one piece having a central aperture adapted for connection with a spigot, the other piece having 45 a discharge tube in alinement with said central aperture, means within said discharge for imparting a whirling motion to a liquid passing therethrough, a reticulated soap container rotatably mounted on said means, 50 a cone shaped imperforate cover for said soap container, and means carried on said cover for imparting a rotary motion to the container by a stream of water directed from the spigot to the apex of the cone-shaped cover. 55

2. A device as herein characterized and consisting of a casing comprising upper and lower separable members, the upper member having an inlet adapted to be connected to a spigot, and the lower member having a discharge or outlet passage, a soap container rotatably mounted in the lower member, said soap container having a cone-shaped cover and curved radial vanes thereon, a spiral fin disposed within the outlet or discharge passage, and means for rotatably mounting said cage on said spiral fin. 60 65
